(57) **CLAIM**

The ornamental design for a decorative mane for a lap desk, as shown and described.

DESCRIPTION

FIG. 1 is a front, elevated, right-quartering perspective view of a particular embodiment of the new design for a decorative mane for a lap desk of the present invention; FIG. 2 is a top plan view of the embodiment shown in FIG. 1;

FIG. 3 is a bottom plan view of the embodiment shown in FIG. 1;

FIG. 4 is a rear elevational view of the embodiment shown in FIG. 1;

FIG. 5 is a front elevational view of the embodiment shown in FIG. 1; and

FIG. 6 is a right side elevational view of the embodiment shown in FIG. 1, the left side elevational view being the mirror image of FIG. 6.

FIG. 7 is a front, elevated, right-quartering perspective view of another particular embodiment of the new design for a decorative mane for a lap desk of the present invention; FIG. 8 is a top plan view of the embodiment shown in FIG. 7;

FIG. 9 is a bottom plan view of the embodiment shown in FIG. 7;

FIG. 10 is a rear elevational view of the embodiment shown in FIG. 7;

FIG. 11 is a front elevational view of the embodiment shown in FIG. 7; and,

FIG. 12 is a right side elevational view of the embodiment shown in FIG. 7, the left side elevational view being the mirror image of FIG. 12.
